UNITED STATES PATENT OFFICE.

ERNEST C. LEWIS, OF MERIDEN, CONNECTICUT, ASSIGNOR TO THE TUBULAR PRODUCTS COMPANY, OF SOUTHBURY, CONNECTICUT, A CORPORATION OF OHIO.

DESIGN FOR AN ASH RECEPTACLE OR ANALOGOUS ARTICLE.

Application filed September 22, 1928. Serial No. 28,249. Term of patent 14 years.

To all whom it may concern:

Be it known that I, ERNEST C. LEWIS, a citizen of the United States, residing at Meriden, in the county of New Haven and State of Connecticut, have invented a new, original, and ornamental Design for an Ash Receptacle or Analogous Article, of which the following is a specification, reference being had to the accompanying drawing, forming a part thereof.

In the drawing:

The figure is a perspective view of an ash receptacle or analogous article showing my new design.

I claim:

The ornamental design for an ash receptacle or analogous article substantially as shown.

In testimony whereof I affix my signature.
ERNEST C. LEWIS.
